CLAIM

The ornamental design for a chest cushion, as shown and described.

DESCRIPTION

FIG. 1 is a perspective view of a first embodiment of the chest cushion;

FIG. 2 is a rear elevation view of the chest cushion of FIG. 1;

FIG. 3 is a front elevation view of the chest cushion of FIG. 1;

FIG. 4 is a right side view of the chest cushion of FIG. 1; FIG. 5 is a left side view of the chest cushion of FIG. 1; FIG. 6 is a top plan view of the chest cushion of FIG. 1; FIG. 7 is a bottom plan view of the chest cushion of FIG. 1; FIG. 8 is a perspective view of the chest cushion of FIG. 1 during use;

FIG. 9 is a perspective view of a second embodiment of the chest cushion with a strap cinching the middle of the chest cushion;

FIG. 10 is a rear elevation view of the chest cushion of FIG. 9;

FIG. 11 is a front elevation view of the chest cushion of FIG. 9;

FIG. 12 is a right side view of the chest cushion of FIG. 9; FIG. 13 is a left side view of the chest cushion of FIG. 9; FIG. 14 is a top plan view of the chest cushion of FIG. 9; FIG. 15 is a bottom plan view of the chest cushion of FIG. 9; and,

FIG. 16 is a perspective view of the chest cushion of FIG. 9 during use.

The broken lines in FIGS. 8 and 16 depict the environment of a woman that forms no part of the claimed design.
